UNITED STATES PATENT OFFICE.

GEORGE C. HELM, OF COLUMBIA, MISSOURI.

DISPLAY DEVICE.

Application filed July 19, 1922. Serial No. 576,082.

To all whom it may concern:

Be it known that I, GEORGE C. HELM, a citizen of the United States, residing at Columbia, in the county of Boone and State 5 of Missouri, have invented certain new and useful Improvements in Display Devices, of which the following is a specification, reference being had to the accompanying drawings.

10 This invention relates to display devices, and more particularly to a fixture for use in displaying a featured article which is on sale.

An important object of the invention is 15 to provide a device of this character which may be employed for displaying an article through a window, door or the like which is ordinarily not used for display purposes.

A further object of the invention is to 20 provide a device of this character which is detachably connected to a door or window and in which the fixture applied to the door or window is such that it does not interfere with the normal operation thereof when the 25 display stand is removed, thereby permitting the use of the display stand at entrances and the like.

A still further object of the invention is to provide a display stand having means 30 whereby the door or window to which it is attached will be illuminated, thereby permitting ready illumination of the entrance doors and the like, which disposed between the display windows of the store, are not 35 ordinarily illuminated and present an unattractive and forbidding appearance.

An additional object of the invention is to provide a device of this character which may be readily attached to a door and detached therefrom, which is pleasing in its 40 appearance, and efficient and durable in service.

These and other objects I attain by the construction and arrangement shown in the 45 accompanying drawings wherein for the purpose of illustration is shown a preferred embodiment of my invention and wherein like reference characters designate like parts throughout.

50 In the drawings:—

Figure 1 is a front elevation of a display bracket constructed in accordance with my invention:

55 Figure 2 is a sectional view partially in elevation showing the device attached to a door; and

Figure 3 is an enlarged section on the line 3—3 of Figure 1.

Referring now more particularly to the drawings, the numeral 10 designates the 60 framing of a door or window, and 11 the usual transparent element held by the framing. 12 indicates an attaching plate secured to the framing of the door or window and having formed thereon spaced loops 13. A 65 bracket is provided consisting of a preferably tubular member 14, the lower end of which is flattened, as indicated at 15, for engagement with the loops 13 of the plate 12, this flattened portion being arranged at 70 a slight angle to the body of the bracket so that the bracket inclines upwardly away from the point of attachment. The upper end of the bracket has secured thereto in any suitable manner an enlarged head 16 75 having an opening 17 formed therethrough.

The numeral 18 designates a shelf having secured to the under surface thereof adjacent its rear edge, a plate 19 which is provided forwardly with an offset portion 20 80 extending in parallel relation to the shelf and adapted to engage in the opening 17 of the head 16. When the offset portion 20 of the plate is engaged in the opening 17, the upper surface of the head 16 abuts the 85 bottom face of the shelf 18, as indicated at 21, to support the same. The rear end of the plate 19 extends slightly beyond the rear edge of the shelf 18 and has formed therein a vertically directed threaded opening 22 90 which is adapted for the reception of the lower end of a conduit or standard 23, the upper end of which is directed downwardly toward the shelf 18 and overhangs the same, as indicated at 24. This upper end forms a 95 support for a lamp socket 25 and a shade 26 directing the rays of a lamp held within the socket downwardly upon the shelf. The conduit 23 serves as a housing for the wiring 27 for the lamp, the lower end of the 100 wiring preferably extending below the lower end of the tubing and being provided with an attaching plug 28.

It will be obvious that with a construction such as hereinbefore described, the shelf may 105 be supported with its forward edge closely adjacent the transparent pane of the door or window in which the exhibitor is employed and that the light directed downwardly upon the shelf will bring the article held 110 thereby into plain view. At the same time the support is of such a character that it

2
presents a pleasing appearance and may be readily attached to or detached from the door so that it will not be in the way during working hours when the door or window, as 5 the case may be, is in use. The upper surface of the shelf is preferably provided adjacent the rear edge thereof with a longitudinally extending slot or kerf 29 adapted for the reception of the lower end of an advertising card, the upper edge of which may 10 rest against the conduit 23 so that the card may be employed for giving the price and similar data with regard to the article, and may at the same time be readily removed. 15 It will be obvious that many changes in the construction as hereinbefore set forth are possible without materially departing from the spirit of my invention and I accordingly do not wish to be understood as limiting 20 myself to such specific structure except as hereinafter claimed.

I claim:

1. In a shelf support, a bracket including a head having an opening therethrough, a 25 shelf having a plate secured thereto, the forward end of the plate being offset from the shelf and engaging in said opening, the upper surface of said head abutting the under surface of the shelf, the offset end of said 30 plate being removable from the opening of said head by movement of said shelf in a plane paralleling said opening.

2. In combination with a door, window or the like embodying a frame and a transparent element held by the frame, an attaching plate secured to the frame and embodying loops, a shelf supporting bracket provided at its lower end with a flattened portion adapted to engage in said loops and 40 maintain the shelf supported thereby with the forward edge thereof adjacent the transparent element held by the frame, said bracket including a shelf attached plate, the rear end of said plate extending rearwardly 45 beyond the rear edge of the shelf, and a lighting standard supported by the rear end of the plate.

3. In combination with a door, window or the like embodying a frame and a transparent element held by the frame, an attaching plate secured to the frame and embodying loops, a shelf supporting bracket

provided at its lower end with a flattened portion adapted to engage in said loops and maintain the shelf supported thereby with 55 the forward edge thereof adjacent the transparent element held by the frame, said bracket including a shelf attached plate, the rear end of said plate extending rearwardly beyond the rear edge of the shelf, said rear 60 end being provided with a vertically directed threaded opening, a conduit engaged in said opening and having its upper end reverted and directed downwardly toward the shelf, a socket carried by said upper end, 65 and lead wires for said socket extending through said conduit.

4. In combination with a door, window or the like embodying a frame and a transparent element held by the frame, a shelf to 70 be supported, an attaching plate secured to the frame below the transparent element and embodying loops, a shelf supporting bracket provided at its lower end with a flattened portion adapted to engage in said loops and 75 extending upwardly from such flattened portion and inclining away from said transparent element, a head at the upper end of said bracket engaging the lower surface of the shelf to support the same with the forward edge thereof in proximity to the transparent element and in vertically spaced relation to the attaching plate, and a plate carried by said shelf and engageable with 80 said head by movement of the shelf in a straight line in one direction, said plate preventing shifting and tilting of said shelf upon said head.

5. In a shelf support, a bracket including a head adapted to engage the under surface 90 of the shelf in spaced relation to the edges thereof and having an opening therethrough, a plate adapted for attachment to the shelf having a forward end portion vertically offset from the body portion thereof and adapted for sliding fit in the opening of said head, the body portion of the plate being 95 adapted to extend beyond the rear edge of the shelf, and a lighting standard supported by the rear end of the body portion of the 100 plate.

In testimony whereof I hereunto affix my signature.

GEORGE C. HELM.
